UNITED STATES PATENT OFFICE.

CARL BERZDORF, OF COLOGNE, GERMANY.

COIN-CONTROLLED TICKET STAMPING AND SUPPLYING APPARATUS.

SPECIFICATION forming part of Letters Patent No. 558,471, dated April 21, 1896.

Application filed October 26, 1895. Serial No. 567,043. (No model.)

To all whom it may concern:

Be it known that I, CARL BERZDORF, a citizen of Germany, and a resident of Cologne, in the Kingdom of Prussia, Germany, have invented certain new and useful Improvements in Coin-Controlled Ticket Stamping and Supplying Apparatus, of which the following is a specification.

Figure 1 is a vertical and Fig. 2 a horizontal section.

Similar letters of reference indicate corresponding parts.

The subject of this invention is an apparatus which, by the insertion of a specific coin without any further manipulation, is caused automatically to provide and deliver a railway traveling-ticket marked with the date or other mode of authentication.

The construction and operation of the apparatus are hereinafter clearly shown and described.

The cards or tickets are arranged to lie one over the other in the box *a*, Fig. 1, while the lowest rests on the line or track *b*, Fig. 2, of the slide *c*, and the antecedent card is already located above the type-stamp *w*. If now a specific coin be put in the slot *d* of the apparatus, it will fall through the funnel *e*, Fig. 1, into the shovel or scoop *f*, which rests on one of the arms of the two-armed lever *g*, which in the normal state carries on its other arm the adjustable counterpoise *h*, which balances the scoop *f*. As soon, therefore, as the coin falls into the scoop *f* the latter overbalances the counterpoise *h* and sinks, whereupon the coin drops into the funnel *N*, (shown in dotted lines in Fig. 1 and in full lines in Fig. 2,) and passes thence into a collecting-box. By the movement of the loaded scoop *f* the spur-pinion *h'*, mounted on the pivot-pin of the lever *g*, causes the depression of the toothed sector *i*, with which it is engaged, whereby the vertical rod *k*, secured to the above-named sector *i*, Fig. 1, presses upon one arm of the stop-lever *m*, pivoting on the pin *l*, so that the other arm thereof is raised, whereby the ratchet-wheel *n* is released by the stop *o*, Fig. 1, and the flier or vane *p* by the stop *p'*, whereby the stop movement of the clock-work is set free. Consequently the motor-work *I* is set free. As soon as one of the steps or notches of the cam-disk

comes into coincidence with a projection on the lever *t*, the latter, actuated by the spring *u*, drops downward, presses upon the lever *v*, Fig. 2, which presses the type-stamp *w* against the card lying over it and makes the desired impression upon the latter. After this impression is completed the other cam-disk *x*, likewise mounted on the same spindle *n* of the ratchet-wheel, presses upon the lever *z*, pivoted on the pin *y*, and by the aid of the rod *A* and lever *B* lifts the rod *C*, and thereby with the stop-lever *D*, secured thereto, so as to release the ratchet-wheel *E* from the projecting stop *F*, Fig. 1, on the lever *D*, so that the stop-motion, consisting of the worm *G* and pin-disk *H*, is released by the raising of the cross-piece *J* of the rod *C*. Thereupon the motor-spring *K*—i. e., the clockwork *I*—is set in action, the cam or wiper wheel *L* is caused to rotate and pushes the slide *c* forward by the aid of the slide-bar *M*, laterally projecting from the slide *c*, to which it is secured. The slide *c* pushes out the undermost card of the card-column *a* lying in front of it and over the type-stamp *w*, while the card just stamped is simultaneously pushed out of the slide-track and drops into the delivery-receptacle *Q*, which projects outside the box or case of the apparatus and can be removed therefrom.

Falling weights can be substituted as motors for the winding-springs *q* and *K*.

Having thus particularly described and ascertained the nature of my said invention and in what manner the same is to be performed, I declare that what I claim is—

In a coin-controlled ticket stamping and supplying apparatus the combination with a clockwork, a balanced scoop-lever combined with an escapement mechanism adapted to cause the disengagement of the said clock-work, a type-stamp, means for raising and depressing the same, a lever combination and a cam-disk arranged to disengage another clockwork, a wiper-disk and a slide, pushing the tickets over the aforesaid type-stamp and thence out off the apparatus.

In testimony that I claim the foregoing as my invention I have signed my name in presence of two subscribing witnesses.

CARL BERZDORF.

Witnesses:

GEORGE COHEN,
WILLIAM H. MADDEN.
